UNITED STATES PATENT OFFICE.

DANIEL KOPS, OF NEW YORK, N. Y.

APPAREL-CORSET.

1,072,862.

Specification of Letters Patent.

Patented Sept. 9, 1913.

Application filed December 6, 1912. Serial No. 735,182.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

My present invention relates to that class of apparel corsets which have skirt extensions below the customary fabric halves of the corset body proper, and particularly to the construction of the front parts of the skirt extensions and the parts associated therewith for the purpose of controlling or reshaping the fleshy upper portions of the limbs of the wearer.

There is a tendency, in the use of corsets having skirt extensions, to force the fleshy portions of the hips and abdomen downwardly to the upper portions of the limbs, sometimes producing a roll of flesh at the lower edge of the corset skirt. This, obviously, is undesirable, not only because of the discomfort caused the wearer, but also because it is noticeable and unsightly, particularly so when a tight-fitting gown is worn.

The object of my present invention is therefore to confine the fleshy upper portions of the limbs and prevent the same from protruding beyond the confines of the corset, the same purpose being sought and the results effected as with the corset construction shown and described in my co-pending application, Serial No. 700,936, filed June 1, 1912.

In the corset constructed in accordance with my present invention, I provide at the front thereof and below the steels and boning, skirt portions extending toward the front steels and having hose supporters connected thereto and extending therefrom, and in line therewith, adapted to be attached to the hose at the inner side portions of the limbs. I also provide flaps overlying the said skirt portions and extending away from the front steels, and these parts are also provided with hose supporters connected thereto and extending therefrom and in line therewith, these hose supporters being adapted to be attached to the hose at the outer side portions of the limbs, and each of the said skirt portions, with its overlying flap,

being adapted to slide, the one over the other, to adjust themselves in various positions, 55 depending upon the tension applied thereto from the hose through the said hose supporters.

In a standing position, when the greatest tension is applied to the part of the corset forming my present invention, the flaps are pulled over the skirt extensions to their greatest extent, whereas when in a sitting position, when the tension of the hose supporters is somewhat relieved, the said skirt 60 extensions and flaps slide, one upon the other, and adjust themselves to various positions, depending upon the tension applied thereto from the hose supporters and the pressure exerted against them by the flesh of 65 the wearer.

In the drawing, Figure 1 is a front elevation of a corset in which my present invention is embodied. Fig. 2 is a similar view of the front portion of a fabric half of a 75 corset illustrating a modified form of the invention, and Fig. 3 is a view similar to Fig. 2 showing a further modification of the invention.

Referring to the drawing and particularly 80 to Fig. 1, 10 and 11 indicate the fabric halves of a corset body, which, as is customary, are provided in front with steels 12 and hooks and eyes 13, by which the halves of the corset may be connected when in use. The fabric half 10 is provided with a skirt 14 and the fabric half 11 with the skirt 15. At the front portion of the corset, the skirt 14 is cut away and extended, forming the member indicated at 16. Similarly the skirt 15 is 85 provided in a corresponding position with the member 17. These skirt extensions 16 and 17 extend toward the corset steels at a predetermined angle thereto, depending upon the stoutness of the person for whom 90 the corset is designed. The extension 16 is provided with a hose supporter 18, which is connected at the end thereof and extends in a line therewith, and is adapted to be secured to the hose at the inner side portion 95 of the right limb. Similarly the skirt extension 17 is provided with a hose supporter 19 which is adapted to be secured to the hose at the inner side portion of the left limb.

Together with the parts hereinbefore described, I also employ flaps, indicated at

20 and 21. The flap 20 is secured to the fabric half 10 of the corset along a line indicated at 22, which is substantially parallel to the corset steel and the line of attachment extends substantially from a point indicated at 23 to a point indicated at 24. This flap 20 is so constructed that when attached to the corset it extends at a predetermined angle away from the corset 10 steels and overlies the skirt extension 16. This flap 20 is provided with a hose supporter 30 connected to the lower end thereof, and extending therefrom in a line with the flap, being adapted to be connected to 15 the hose at the outer side portion of the right limb. Similarly the flap 21 is secured to the fabric half 11 along the line indicated at 25, which extends from a point indicated at 26 and a point indicated at 20 27. This flap 21 is provided with a hose supporter 31 connected to the end thereof and extending therefrom in a line therewith, being adapted to be secured to the hose at the outer side portion of the left limb, the flap 25 21, like the flap 20, extending in a line away from the corset steels and overlying the skirt extension 17. The angles at which the flaps 20 and 21 extend away from the corset steels is also dependent upon the 30 stoutness of the wearer for whom the corset is designed, and these flaps 20 and 21 may be provided with eyelets 28 and the front portions of the fabric halves of the corset with hooks 29, by which the free ends 35 of the flaps may be secured in position to the fabric halves in the corset body.

From the foregoing description, it will be seen that the hose supporters 18 and 30 are adapted to engage the hose respectively 40 at the inner side and outer side portions of the right limb, and the hose supporters 19 and 31 to engage the hose respectively at the inner side and outer side portions of the left limb, and as will be apparent, when 45 in a standing position of the wearer, these parts will assume, under the maximum tension to which they are subjected, the positions as shown in Fig. 1 of the drawing, whereas in a sitting position, or in intermediate positions, when the tension of the hose supporters is more or less relieved, the pressure exerted against these parts by the flesh 50 of the body will cause the skirt extensions and flaps to slide, the one over the other, and to adjust themselves to a position depending upon the tension applied thereto 55 and the pressure exerted against them by the body of the wearer.

Referring to Fig. 2, it will be seen that 60 the skirt extension 16 and the hose supporter 18 connected thereto, are in all respects identical with the same parts as hereinbefore described in connection with Fig. 1. The flap, which in this figure is

indicated at 32, however, while of the same 65 general configuration as the flap 20, may be connected to the corset body 10 along a plurality of lines; for example, the flap 32 is connected to the corset body along the lines 34, 35 and 36, which extend between the 70 points 37, 38, 39 and 40. The flap 32 has connected thereto a hose supporter 48, which is similar in all respects to the hose supporter 30, connected to the flap 20, and the 75 functions performed by parts of the corset, as indicated in Fig. 2, are precisely the same as those heretofore described in connection with the construction shown in Fig. 1, it being understood that the other fabric 80 half of the corset is similarly constructed.

Referring to Fig. 3, it will be seen that the flap 33 is constructed similarly to the flap 32, shown in Fig. 2, that is to say, it is connected to the fabric half 11 of the corset along the lines 41, 42, and 43, which 85 extend between the points 44, 45, 46, and 47. In this construction, however, the skirt extension 50 is not separated from the lower front portion of the fabric half of the corset, but is connected thereto or formed integral therewith. In this form of the invention, the hose supporter 51, corresponding to the hose supporters 18 and 19, in the other constructions, is connected to the skirt extension 50 and extends therefrom in a 90 more nearly vertical line but nevertheless is adapted to be attached to the hose at the inner side portion of the left limb of the wearer. Obviously also, the other fabric half of a corset of this construction is the 95 duplicate, with the parts reversed, of that shown in Fig. 3.

I claim as my invention:

1. In an apparel corset, a corset body half having a depending skirt, a portion of 105 which extends toward the front steel of the corset body half and terminates in an unattached end, a member overlying the said portion and extending away from the front steel of the corset body half, and hose supporter devices connected to and extending from the said portion and overlying member and adapted respectively to be attached to the inner side portion and the outer side portion of the hose on the corresponding 110 limb of the wearer.

2. In an apparel corset, a corset body half, a skirt depending therefrom, a portion of the said skirt below the front steel and boning extending toward the front steel 115 and terminating in a free end at a point below the lower extremity of the front steel, a hose supporter connected to and extending from the free end of the said skirt portion and adapted to be connected to the 120 hose on the corresponding limb of the wearer at the inner side portion thereof, a flap secured to the corset body half and ex- 125

tending away from the front steel thereof and overlying the said skirt portion, and a hose supporter attached to and extending from the lower end of the said flap and 5 adapted to be connected to the hose on the same limb of the wearer and at the outer side portion thereof.

Signed by me this 2nd day of December, 1912.

DANIEL KOPS.
